DESIGN FOR A GLIDER FRAME

Louis Vavrik, Rossford, Ohio, assignor to The Hettrick Manufacturing Company, Toledo, Ohio, a corporation of Ohio

Application May 10, 1937, Serial No. 69,254

Term of patent 7 years

To all whom it may concern:

Be it known that I, Louis Vavrik, a citizen of the United States and resident of Rossford, county of Wood, State of Ohio, have invented a new, original, and ornamental Design for a Glider Frame, of which the following is a specification, reference being had to the accompanying drawing forming a part thereof.

Figure 1 is a perspective view of the glider frame, showing my new design; and

Figure 2 is an end elevation of the glider frame.

I claim:

The ornamental design for a glider frame substantially as shown.

LOUIS VAVRIK.
